FOOD MOLDING RING

Richard A. Boucher, Northboro, Mass., assignor to
Dart Industries Inc., Los Angeles, Calif.

Filed Aug. 16, 1973, Ser. No. 388,851

Term of patent 14 years

Int. Cl. D7—04

U.S. Cl. D7—43

FIG. 1

FIG. 2

*FIG. 3.**FIG. 4.*

FIG. 1 is a top plan view of a food molding ring showing my new design;

FIG. 2 is a side elevational view thereof;

FIG. 3 is a bottom plan view thereof; and

FIG. 4 is a cross-sectional view thereof taken along line 4—4 of FIG. 2.

I claim:

The ornamental design for a food molding ring, substantially as shown.
